THOMAS F. VINDAL,
INVENTOR:

BY *Victor J. Evans*,

ATTORNEY.

WITNESS: *Miss Ford.*

UNITED STATES PATENT OFFICE

1,937,178

FUSE

Thomas Francis Vinal, New York, N. Y.

Application July 19, 1929, Serial No. 379,467
Renewed May 29, 1933

1 Claim. (Cl. 200—121)

This invention relates to fuses and has particular reference to fusible material for carrying electrical current.

One of the objects of the invention is to provide a removable member for installment in an electric circuit, which includes a fusible element for breaking the circuit, with a filament connected in parallel with the said element, so that on the latter being fused the filament is thereby placed in series in the circuit to accommodate the flow of current and visibly indicate the break in the fuse.

Another object of the invention is the provision of a fuse which contains a fusible element having sections of different current carrying capacity, so that a filament having its terminals in shunt on sections of large carrying capacity may be automatically placed in series with said sections on the fusing of an interposed section of reduced carrying capacity.

A further object of the invention is to provide a vacuum chamber in a fuse plug in which a filament is installed together with a fusible element. Ordinarily the latter element carries the electric current, owing to the increased resistance offered by the filament, but on the said element being fused the filament carries the current and thereby gives forth light to indicate the breaking of the fusible element.

A still further object of the invention is the provision of a fuse of the above described character which is simple in construction, efficient and durable for the purpose intended, and inexpensive to manufacture.

With these and other objects in view the invention resides in certain novel constructional features, the essential characteristics of which, hereinafter fully described, and particularly pointed out in the appended claim, are illustrated in the accompanying drawing, in which:—

Figure 1 is a perspective view of my improved fuse plug.

Figure 2 is an enlarged longitudinal sectional view thereof.

Figure 3 is a perspective view of the fusible element and filament.

Figure 4 is a wiring diagram.

Referring particularly to the drawing by reference characters, the numeral 10 designates the fuse in its entirety, the body 11 of which is constructed of porcelain, hard rubber or other insulating material, is formed with a central chamber 12.

The body 11 is provided with a metallic sleeve 55 or covering, which is formed with screw threads

13 for engagement with coacting threads in the usual socket member, while a terminal 14 is also carried by said body. Electric current emanating from a source 15 flows through wiring 16, which is connected with the screw threads of 60 said socket member, and through the threads 13. A fusible element 17 contacts with said threads 13 and with the terminal 14, and as the latter terminal contacts with a terminal in the usual socket member, which is connected with 65 a continuation 18 of the wiring, current is transmitted to any current consuming device such as a lamp 19, there being a switch 20 in the circuit.

The element 17 is constructed with a pair of sections 21, 22 of like current carrying capacity 70 while, between said sections and preferably integral therewith, a reduced portion 23 of less carrying capacity is formed. Contacting with the sections 21, 22 in parallel with the element 17, and bridging the section 23, is a filament 24 of 75 tungsten or the like. As the material of the filament 24 is of higher resistance than the material of the element 17, current flows through the latter while said filament remains unheated; and as the carrying capacity of the sections 21 and 22 80 is greater than that of the inner section 23, said latter section fuses when the current impressed on the circuit reaches a certain predetermined density. After the section 23 has fused or melted to normally break the circuit, current flows in the 85 filament, thereby heating the latter to incandescence and giving forth light.

In order to fully utilize the filament for displaying a visible signal, and to clearly distinguish a fused element from others, when a number of 90 fuses are used together, I prefer to utilize the chamber 12 as a vacuum chamber, but an inert or non-combustible gas may be used in said chamber without departing from the invention. The body 11 is therefore formed with an annular 95 step or shoulder 25, on which, with a ring or collar 26, a disc 27 of glass or other suitable transparent material is sealed.

While I have described what I deem to be the most desirable embodiment of my invention, it is 100 obvious that many of the details may be varied without in any way departing from the spirit of my invention, and I therefore do not limit myself to the exact details of construction herein set forth nor to anything less than the whole of my 105 invention limited only by the appended claim.

What is claimed as new is:—

A fuse plug comprising a body member formed with end and peripheral contacts for engagement with the contacts in a fuse block, the body mem- 110

ber being hollowed out to provide a chamber, a transparency closing the chamber at the end remote from the center contact and having an air-tight connection with the body member to preclude the entrance of air to the chamber, a fuse disposed interior to the chamber and connecting the center and peripheral contacts and reduced in cross section at a fixed point to insure its rupture at that point, and a filament disposed centrally in the chamber for observation through the window and shunting that portion of the fuse of reduced cross section.
